Ahmed Alhafidh(57) **CLAIM**

The ornamental design for a bottle, as shown and described.

DESCRIPTION

FIG. 1 is an orthographic view of a bottle, showing my new design, the facemask shown removed from the bottle for ease of illustration;

FIG. 2 is an elevational view of a front side of the bottle of FIG. 1;

FIG. 3 is an elevational view of a back side of the bottle of FIG. 1;

FIG. 4 is an elevational view of a right side of the bottle of FIG. 1;

FIG. 5 is an elevational view of a left side of the bottle of FIG. 1;

FIG. 6 is an elevational view of a top side of the bottle of FIG. 1;

FIG. 7 is an elevational view of a bottom side of the bottle of FIG. 1;

FIG. 8 is a perspective view of the bottle of FIG. 1 with a facemask coupled to the helmet;

FIG. 9 is a rear perspective view of the facemask shown removed from the bottle for ease of illustration;

FIG. 10 is an elevational view of the front side of the bottle of FIG. 8;

FIG. 11 is an elevational view of the left side of the bottle of FIG. 8;

FIG. 12 is an elevational view of the top side of the bottle of FIG. 8; and,

FIG. 13 is an elevational view of the bottom side of the bottle of FIG. 8.

The broken lines in the drawings illustrate a portion of the bottle which form no part of the claimed design.
